UNITED STATES PATENT OFFICE.

EMIL FILLMANN, OF CHICAGO, ILLINOIS.

DESIGN FOR A MOLDING FOR A PICTURE-FRAME.

SPECIFICATION forming part of Design No. 14,376, dated October 30, 1883.

Application filed August 27, 1883. Term of patent 3½ years.

To all whom it may concern:

Be it known that I, EMIL FILLMANN, a citizen of the United States of America, residing at Chicago, in the county of Cook and State of Illinois, have invented and produced a new and original Design for Moldings, of which the following is a specification, reference being had therein to the accompanying illustration.

10 The molding as illustrated in the print, which is a perspective of the same, consists of the base proper, a crown-mold, a scotia, a panel, and a bed-mold, each part shaped and ornamented as will be described.

15 A represents the base of the molding, which is curved at its rear, as shown.

B is the crown-mold, which is ornamented with a series of leaves, a, arranged in pairs, said leaves being placed flat upon the upper 20 surface of the crown-mold, and each pair being divided from the adjoining pair by an arch, b, as shown.

C represents a strip which separates the crown-mold from the scotia D. This scotia is

ornamented with a series of irregular bars or 25 strips, interwoven with which are vines and flowers. Scotia D is divided by a beveled strip, E, from a panel, F, said panel presenting a rolling upper surface, as shown. This panel and the bed-mold G are divided by a 30 strip, H.

In this application I lay no claim to a molding consisting of the parts named, as such a claim has been made by me in another application filed on even date herewith; but 35

What I do claim is—

In a design for a molding, consisting of an ornamental scotia and a crown and bed mold, a sanded panel presenting a rolling upper surface, the several parts separated by dividing strips, as described.

In testimony whereof I affix my signature in presence of two witnesses.

EMIL FILLMANN.
